UNITED STATES PATENT OFFICE.

FREDERICK A. HENDERSON, OF CRESTON, IOWA.

DRYING-ROOM FOR RUGS, CARPET, AND THE LIKE.

1,238,517.

Specification of Letters Patent. Patented Aug. 28, 1917.

Application filed August 17, 1916. Serial No. 115,407.

To all whom it may concern:

Be it known that I, FREDERICK A. HENDERSON, a citizen of the United States, residing at Creston, in the county of Union 5 and State of Iowa, have invented certain new and useful Improvements in Drying-Rooms for Rugs, Carpet, and the like, of which the following is a specification.

This invention relates in general to a drying-room for rugs, carpet and the like after they have been cleaned.

The main object of this invention is to equip the drying-room with simple, economical, durable and efficient elevating and supporting devices; a conveying device, and a device for steaming the rugs and carpet as they are conveyed to the front or outlet of the room.

Another object of the invention is to provide novel means for suspending any suitable number of rugs or pieces of carpet within the room in such a manner that any one of the suspended pieces may be raised or lowered at any time without disturbing 25 any of the other suspended pieces within the room, and as each piece is lowered it will be automatically conveyed toward the outlet portion of the room and will be subjected to the steaming process during its 30 exit instead of taking it to another part of the plant as is usually done.

The foregoing and such other objects as may appear from the ensuing description are attained by the novel features of construction, combination, arrangement and location of the parts, hereinafter fully described, illustrated in the accompanying drawings, and particularly pointed out in the claims appended hereto, it being understood 35 that slight changes in the form, proportion, and minor details may be resorted to without departing from the spirit or sacrificing any of the advantages of the invention.

45 In the accompanying drawings it will be seen that:

Figure 1, is a perspective view showing the improvements embodying my invention.

Fig. 2, is a longitudinal sectional view 50 showing the lower portion of my improved drying-room and the improved devices employed therein.

Fig. 3, is a detail view showing the operating shaft partly in section; the spools secured to said shaft in longitudinal section, 55 and the belt pulley in sectional elevation.

Fig. 4, is a detail view showing a cross-section through the operating shaft and one of the spools, showing the means for securing the spool to the shaft. 60

Fig. 5, is a detail view showing in cross-section the means for clamping one end of the rug or carpet to be suspended in its closed and locked position.

Fig. 6, is a detail view showing the clamping means in the unlocked and open position, and 65

Fig. 7, is a detail side view of the clamping means in its closed and locked position.

Similar numerals of reference are employed to designate corresponding parts throughout the several figures of the drawings. 70

In carrying out my invention as illustrated, the numeral 1 indicates the room intended to receive and support in a suspended position any suitable or desirable number of rugs or pieces of carpet after they shall have been properly cleaned, said room being heated in any suitable or desirable manner. 75

Suitably supported by the side walls of the room and running the full width of said room is a removable metal shaft 2, provided at one end with a handle 3, for rotating the said shaft, and on this shaft is arranged any suitable or desirable number of iron spools 4, which can be attached at will, and secured thereto by a split key 5, which passes through an opening in the spool and shaft, and wound around each of said spools 4, is a rope 6 by which the rug and carpet clamping means hereinafter described are properly elevated and lowered. 80

Arranged above the shaft 2 and slightly to the rear thereof is a bar or rod 7, running the full width of the room, and secured to the lower portion of said bar or rod is a series of eyes 8, each eye supporting a hook 9, and each hook being adapted to engage with an eye 10 carried by each of the spools 4, whereby each spool is prevented from unwinding and thereby lowering the suspended piece when the spool is disconnected from the shaft by the removal of the split key 5. 95

It will be understood that two spools 105 are arranged on the shaft for each rug or piece of carpet the room is intended to have suspended therein, and while I have shown but three rugs suspended, it will be obvious that the room may be constructed as large 110 as desired, and the spools may be made of any suitable size, so that any suitable or

desirable number of rugs or pieces of carpet may be suspended within the room.

Running from each of the spools 4 is a rope 6, which passes through eyes or small pulleys 11 secured at suitable points to the ceiling of the room, the upper end of each rope being secured to an eye 12 fastened to the clamping means which is adapted to clamp the upper end of each rug or piece 10 of carpet.

Each of the clamping means consists of two wooden boards 14 and 15 extending substantially the entire width of the room and provided with a hinge 16 near each end 15 thereof, whereby they are hinged together, and along the inner lower edge portion, each board is provided with a series of teeth 17, the outer board 15 carrying a plurality of metal bolts or pins 18, each of said bolts 20 or pins having secured at one end thereof a button 19, which passes through an oblong opening 20 in the inner board 14, so that when said boards 14 and 15 assume a position near the floor of the room and are 25 opened or separated on their hinges, the edge of the rug or carpet is laid on the teeth of the lowermost board, the top board is then shut down on the rug, and the plurality of buttons are thus caused to protrude 30 through the oblong holes or openings 20 registering therewith, and when the clamping means has been completely closed the buttons are just flush with the outer surface 35 of the outer board 15, then in order to securely fasten and clamp the rug between the said boards it is simply necessary to turn each of said buttons crosswise of the oblong openings 20, when the elevating means may be operated and the rug properly suspended 40 within the room.

Near the lower portion or floor of the room is arranged a conveyer which consists of an endless belt 21 of canvas or other suitable material extending substantially 45 the width of the room, said endless belt being supported by and operated on by two wooden rollers 22 and 23, each being supported by the side walls of the room and located at the bottom portion of the room. 50 The shaft 2 is provided near one end thereof with a pulley 24, around which is secured an endless driving belt 25 of any suitable material, said belt 25 passing beneath and partially around each of the rollers 22 and 55 23, hence the rotation of the shaft 2, through the medium of the belt 25 operates the endless conveyer belt 21.

At the front end portion of the room and running the full width thereof is a wooden 60 steam box 26 about three inches deep and about five inches wide provided with a perforated metal top 27, having a steam inlet pipe 28, and a drain pipe 29 connected thereto.

It will be readily perceived that the iron

spools can be so arranged on the shaft 2 and the ropes connected to the clamping means in such a manner than any one of the rugs in the room can be raised or lowered at any time by turning the shaft without disturbing any of the other rugs within the room. 70

When it is desired to elevate or suspend a rug, the rug clamping means is caused to assume a position near the floor, one end 75 of the rug is securely fastened to the said clamping means, when by turning the shaft 2 the conveyer belt 21 is operated and assists in conveying the rug to a position substantially in a vertical line with the suspended position the rug is intended to occupy in the room, and at the same time the winding spools and ropes are elevating the rug to its suspended position, and when it is desired to lower a rug from the rear position of the room, as soon as the shaft 2 is turned to lower the rug, the driving belt 25, automatically operates the conveyer belt 21, so that when the lower edge of the rug 80 contacts with the conveyer it is immediately 85 carried toward the front of the room, which eliminates the necessity of an extra man to catch the bottom of the rug and carry it out, and as the rug is conveyed across the steam box, steam is turned on and the steaming process thus attended to as the rug is being lowered, instead of taking it to some other 90 part of the plant. After the rug has been cleaned and dried the live steam serves to soften the pile or nap, and by constant 95 sweeping all the while the rug is passing across the steam box on its way out of the room and while the live steam is coming up through from the under side, the surface or nap is put in a nice soft fluffy condition. 100

Having thus described my invention what I claim and desire to secure by Letters Patent is:—

1. In a drying room for rugs and the like, means for elevating and lowering the rugs 110 supported by the walls of the room, conveyer means connected to and operated by the elevating and lowering means, and a steam-box located at one end of said conveyer means. 115

2. In a drying room for rugs and the like, means for elevating and lowering the rugs consisting of a shaft removably supported by the walls of the room, rug clamping means, a plurality of winding spools removably supported on said shaft, means within the room and connected to each of said spools to prevent unwinding of the spools, conveyer means connected to and operated by the elevating and lowering means, and a 120 plurality of ropes leading from said spools over supports fastened to the ceiling and secured to the said rug clamping means. 125

3. In a drying room for rugs and the like, means for elevating and lowering the rugs, 130

consisting of a shaft removably supported by the walls of the room, rug clamping means, a plurality of winding spools removably supported on said shaft, means connected with each spool to prevent unwinding of the same, a plurality of ropes leading from said spools over supports fixed to the ceiling and secured to said clamping means, and a conveyer located near the floor of the room connected to and operated by said elevating and lowering means.

4. In a drying room for rugs and the like, means for elevating and lowering the rugs comprising a shaft removably secured to the walls of the room, a plurality of winding spools removably secured on said shaft, means connected with each spool to prevent unwinding of the same, a plurality of ropes leading from said spools over supports fixed to the ceiling, the upper end of each rope being fastened to a rug clamping means, said rug clamping means consisting of two boards hinged together having a series of teeth at the inner lower edge thereof, and carrying a plurality of clamping means for locking the boards in closed position, and conveyer means connected to and operated by the said elevating and lowering means.

5. In a drying-room for rugs and the like, removable means supported by the walls of the room for elevating and lowering the rugs, a conveyer located near the floor of the room connected to and operated by the ele-

vating means, a steam box at the bottom of the room near one end of said conveyer, and rug clamping means consisting of two boards hinged together having a series of teeth at the inner lower edge thereof, and carrying a plurality of bolts and buttons for locking the boards in closed position to the rug.

6. In a drying-room for rugs and the like, means for elevating and lowering the rugs comprising a removable shaft secured to the walls of the room, a plurality of winding spools removably supported in said shaft, rug clamping means, a plurality of ropes leading from the winding spools over fixed supports in the ceiling and fastened to said clamping means, and means located above and at the rear of said shaft for connecting with each of said spools to prevent the unwinding of the same.

7. In a drying-room for rugs and the like, means for elevating and lowering the rugs consisting of a removable shaft secured to the walls of the room, a plurality of winding spools removably secured on said shaft, rug clamping means, a plurality of ropes leading from the winding spools over fixed supports in the ceiling and fastened to said clamping means, and an endless conveyer belt located near the bottom of the room connected with and operated by a driving belt connected to said shaft.

FRED A. HENDERSON.
